UNITED STATES PATENT OFFICE

GEORGE W. O'KEEFFE, OF MILTON, MASSACHUSETTS, ASSIGNOR TO CONDIT ELECTRICAL MANUFACTURING CORPORATION, OF SOUTH BOSTON, MASSACHUSETTS, A CORPORATION OF MASSACHUSETTS

THERMAL RELAY AND CUT-OUT

Application filed February 17, 1930. Serial No. 428,911.

This invention relates to thermal cut-outs or relays of the type having an electrically heated fusible element which operates to control an auxiliary electric circuit, which, usually, is the pilot circuit of an electrically operated circuit interrupter, and a heating element which is included in the circuit to be protected for heating the fusible element.

One of the objects of the present invention is the provision of a thermal cut-out or relay wherein the fusible element is located alongside and is closely adjacent the heating element.

Another object of the invention is the provision of a thermal cut-out in a tubular insulating casing having end terminals between which a heating element is connected and an intermediate terminal between which and one end terminal a fusible element is removably connected.

A further object is the provision of a thermal cut-out of the type above set forth having simple and improved means by which the fusible element can be removed after it has operated; and specifically a cut-out having an enclosing tubular shell through which a heating element is extended and having a fusible element provided with attaching portions disposed adjacent the surface of the casing shell where they are readily accessible and an offset heat-absorbing portion that is located substantially in the longitudinal axis of the casing alongside the heating element.

In the usual thermal cut-out it is necessary to practically completely dismantle the device in order to replace the fusible element, and it constitutes another object of this invention to provide a cut-out wherein the fusible element is accessible through the side wall of the casing shell by the removal of one terminal cap and without otherwise disturbing the assembly of the cut-out.

A still further object is the provision of a thermal cut-out having a fusible element and a heating element for heating the fusible element either of which can be replaced without disturbing the other.

A yet further object is generally to improve the construction and operation of ther-

mal cut-outs and relays for the control of electrically operated switches.

Fig. 1 is a plan view, partly in section, of a cut-out embodying the invention.

Fig. 2 is a view similar to Fig. 1 showing an end cap partly removed.

Fig. 3 is a longitudinal sectional elevation of the cut-out of Fig. 1.

Fig. 4 is a section on line 4-4 of Fig. 3.

Fig. 5 is a section on line 5-5 of Fig. 3.

Fig. 6 is a perspective view of the inner insulating and terminal supporting tube.

Fig. 7 is an end view of a terminal washer.

Fig. 8 is a perspective view of the fusible element.

Fig. 9 is an elevation showing a modified construction for the heating and fusible elements.

Fig. 10 is an end view of a terminal washer for the modification shown in Fig. 8.

Fig. 11 is a single phase wiring diagram showing the cut-out of the invention associated with the pilot circuit of an electrically operated switch.

As herein shown, the thermal cut-out or relay embodying the invention includes an inner tubular shell 10 of insulating material which has exteriorly threaded terminal ferrules 12 and 14 permanently fixed on its opposite ends by means of rivets 16 which pass through said ferrules and tubular member. Internally screw threaded terminal caps 18 and 20 are removably screw threaded on said ferrules 12 and 14 respectively and constitute the line terminals of the cut-out. As shown most clearly in Fig. 6, the inner tubular shell 10 is formed with a longitudinal slot 22 in its upper wall which extends substantially along the length of the tube and which terminates in the shoulder 24. An intermediate terminal member comprising a metal ring 26 closely surrounds the tube 10 and has a U-shaped inwardly directed peripheral portion 28 that is adapted to be received closely within the end of the slot 22 of said insulating tube 10 adjacent the shoulder 24 thereof. The bottom of said U-shaped portion 28 constitutes a flat terminal seat 30 which is provided with an attaching screw 32 by means of which one end of the fusible element hereinafter to be de-

65

In assembling the cut-out, the end ferrule 12 is first riveted to the insulating tube 10 after which the spacing ring 34, the intermediate terminal 26, and the outer tubular casing 72 are placed in position on the inner tube 10. The terminal ferrule 14 and the terminal block 38 are then secured in position on the tube 10 by means of rivet 16. The assembly of the heating element is obvious. The fusible element is placed in position, after the outer casing 72 has been rotated to uncover the slot 22 in the inner tube 10, by slipping one end thereof under the annular end portion 78 of the outer casing and securing it by the terminal screws 42 and 32 to its respective terminal seats. The heating element can also be inserted in place by threading it through the casing openings, without the necessity for rotating the outer casing to bring its slot into alignment with the slot in the inner tube.

From the above description, it will be evident that by removing both terminal caps the heater element can be removed from the casing without disturbing the fusible element, and that the fusible element can be removed and replaced simply by removing the right-hand end cap 20 without disturbing the assembly of the heating element.

In Figs. 9 and 10, a modified construction is shown for the heating element. As here shown, the heating element 60a comprises a flat strip of resistance material having its ends 62a passed through slots 64a in metal terminal discs 66a and reflexed to provide the clamping portions 68a as in the previous construction. A flat strip 70a of electrically insulating material, as mica, is disposed between the heating element 60a and the fusible element.

In Fig. 11, the cut-out of the invention is shown associated with an electrically operated switch 80 for controlling the power circuit 58 of a single phase motor circuit. The switch 80 includes the pairs of stationary contact members 82 and the bridging or brush members 84 therefor which are movable into and out of bridging engagement by a solenoid 86 acting through a toggle connection 88 with the movable bridging members. Said solenoid 86 includes an energizing coil 90 which also constitutes a holding coil for maintaining the breaker releasably in its circuit closing position. The heating element 60 of the cut-out embodying the invention is adapted to be heated by the current flowing in the motor circuit 58 and, to this end, the end terminal caps 18 and 20 comprising the line terminals of the cut-out, are connected in the circuit 58 so as to include the heating element 60 in series therewith. The fusible element including the links 45 and 46 is connected in series with the holding coil circuit including the winding 90 of solenoid 86. As thus arranged, when an overload flows in the motor

circuit 58 of sufficient magnitude to heat the offset portions 52 of the fusible element and melt the solder 56 constituting the electrical connection therebetween, the parts of the fusible element will snap apart and the circuit through the holding coil 90 will be interrupted and the breaker 80 will open its circuit. The manual control means 92 including a starting switch 94 and a stopping switch 96 may be provided as is customary for controlling the opening and closing of the switch. The circuit connections herein shown constitute no part of the present invention.

It will be noted that in both constructions herein illustrated the fusible element is disposed alongside and is closely adjacent the heating element, while the attaching portions 48 thereof are located near the surface of the casing where they are readily accessible.

Various modifications may be made in the construction and arrangement of the parts without departing from the scope of the invention.

I claim:

1. A thermal relay comprising a pair of spaced fixed supports, a thermal element comprising two sections having their adjacent ends united by a fusible material and having their remote ends secured to said supports, and a heater element which is extended along the length of and close to said thermal element and on one side only thereof, one of said sections of said thermal element being resilient and being held under stress to its support and adapted to snap away from the co-operating section and also away from said heater element when said fusible material melts.

2. A thermal relay having an enclosing casing, an electric heating element therein, removable discs located at the ends of said casing constituting supports for the ends of said heating element, removable end caps on said casing holding said discs removably in place, and a fusible element located within said casing in heat-receiving relation with said heating element.

3. A thermal cut-out including an enclosing casing having end terminal members, a heating element electrically connecting said terminal members, a fusible element disposed alongside and closely adjacent said heating element and electrically connected with one of said end terminal members, and an intermediate terminal member carried by said casing and electrically connected with the other end of said fusible element.

4. A thermal cut-out including a tubular insulating enclosing casing having end terminal members, a heating element extended through said casing and electrically connected at its ends with said terminal members, a fusible element located substantially in the longitudinal axis of said casing alongside and

- in proximity to said heating element and having one end thereof electrically connected with an end terminal member of said casing, and an intermediate terminal member carried by said casing and electrically connected with the other end of said fusible element. 5
5. A thermal cut-out including a tubular enclosing casing having end terminal members and an intermediate terminal member, a heating element extended through said casing eccentrically thereof and electrically connected at its ends with said end terminal members, a fusible element centrally disposed within said casing alongside said heating element and having one end thereof connected electrically with an end terminal member of said casing and having its other end electrically connected with said intermediate terminal member. 10
6. A thermal cut-out including an enclosing casing having end terminal members, a heating element extended through said casing and connected electrically with said terminal members, an intermediate terminal member carried by said casing, and a thermal element comprising two sections having their adjacent ends united by a fusible material disposed alongside said heating element and having one end thereof connected with an end terminal member of said casing and the other end with said intermediate terminal, one of said sections of said thermal element being resilient and being held under stress to its cooperating terminal and adapted to snap away from the cooperating section and also away from said heating element when said fusible material melts. 15
7. A thermal cut-out including an enclosing insulating shell having end terminal members, a heating element extended through said shell and connected electrically with said terminal members, an intermediate terminal member carried by said shell, a fusible link disposed in said casing alongside said heating element and closely adjacent thereto, means connecting the opposite ends of said link to an end terminal member and to said intermediate terminal member, said insulating shell having provision for the removal of said fusible link through the top thereof. 20
8. A thermal cut-out including a tubular enclosing casing having end terminal members and an intermediate terminal member, a heating element in said casing extended between and electrically connected with said end terminal members, and a fusible element in said casing extended between and electrically connected with an end terminal member and said intermediate terminal member. 25
9. A thermal cut-out including a tubular enclosing casing having end terminal members and an intermediate terminal member, a heating element extended longitudinally through said casing and connected electrical- 30
- ly with said end terminal members, and a fusible element disposed in the axis of said casing and electrically connecting said intermediate terminal member and one of said end terminal members. 35
10. A thermal cut-out including a tubular enclosing casing having end terminal members and an intermediate terminal member, a heating element extended longitudinally through said casing and connected electrical- 70
- ly with said end terminal members, a fusible element disposed in the longitudinal axis of said casing and electrically connected with said intermediate terminal member and an end terminal of said casing, said heating element and fusible element arranged to lie 75
- alongside and closely adjacent each other. 80
11. A terminal cut-out including a tubular enclosing casing having a longitudinal slot in a side wall thereof, terminal caps removably secured to the ends of said casing, a third terminal member intermediate said end caps, a fusible element disposed in said casing beneath the slots therein and electrically connected at its ends with said third terminal and one of said end caps and a heating 85
- element extended longitudinally through said casing closely adjacent said fusible element and electrically connected with said end caps. 90
12. A thermal cut-out including an enclosing casing having a longitudinal slot in a wall thereof, terminal ferrules fixed to the ends of said casing, end caps removably received on said ferrules, a third terminal disposed intermediate said terminal ferrules, a fusible element having its ends connected electrically to said third terminal and one of said end ferrules, and a heating element extended through said casing and secured electrically at its ends with said end caps. 95
13. A thermal cut-out including an enclosing casing of insulating material having a longitudinal slot therein, terminal members comprising line terminals at the ends of said casing, a third terminal member surrounding said casing intermediate its ends, a fusible element disposed in said casing beneath said slot and electrically connecting said third terminal and one of said end terminal members, a heating element extended longitudinally through said casing and connected electrically with the end terminals thereof, said fusible element having a portion thereof which is parallel with and is closely adjacent said heating element, and insulating means separating said heating element and fusible element. 100
14. A thermal cut-out including a tubular enclosing casing having a longitudinal slot in a wall thereof, terminal ferrules carried by said casing at the ends thereof, one of said ferrules having a slot which is coincident with the slot in said casing, a terminal block disposed in said casing having a terminal attaching portion disposed beneath the slot in said casing, a third terminal disposed exteriorly 105
- 110
- 115
- 120
- 125
- 130

- of said casing intermediate its ends, said third terminal having a peripheral portion which is received within the slot of said casing and which is provided with a terminal attaching portion, a fusible element extended between 5 said third terminal and said terminal block and having its ends detachably secured to the terminal attaching portions thereof, end caps removably screw threaded on said terminal ferrules, one of said end caps forming a removable closure for the sloited end of said casing, and a heating element extended longitudinally through said casing and connecting electrically with said end caps. 10
15. A thermal cut-out including a tubular enclosing casing having a longitudinal slot in a wall thereof, terminal ferrules carried by said casing at the ends thereof, one of said ferrules having a slot which is coincident with the slot in said casing, a terminal block disposed in said casing having a terminal attaching portion disposed beneath the slot in said casing, a third terminal disposed exteriorly of said casing intermediate its ends, 20 said third terminal having a peripheral portion which is received within the slot of said casing and which is provided with a terminal attaching portion, a fusible element extended between said third terminal and said terminal block and having its ends detachably secured to both, end caps removably screw threaded on said terminal ferrules, a heating element extended longitudinally through said casing and connecting electrically with said 25 end caps, and a tubular outer casing which surrounds and is rotatable on said tubular casing. 30
16. A thermal cut-out including a tubular longitudinally-slotted enclosing casing having terminal ferrules at the ends thereof, and an intermediate terminal member having an external thermal seat disposed within said casing beneath the slot therein, a terminal block located in the end of said casing and 40 electrically connected with an end ferrule thereof having a terminal seat disposed beneath the slot, a fusible link extended between the terminal seats of said intermediate terminal member and block having an off-45 set heat-absorbing portion disposed substantially in the longitudinal axis of said casing, a heating element extended longitudinally through said casing, a removable cover for the slot in said casing, and terminal caps 50 screw threaded on said ferrules and separately connected electrically with the opposite ends of said heating element. 55
17. A thermal cut-out of the cartridge type including an inner tubular casing having a longitudinal slot therein, terminal ferrules carried exteriorly of said tube at the ends thereof, one of said ferrules having a slot coincident with the slot in said casing, a terminal block disposed within said tube at the 60 end thereof and electrically connected with 65
- said slotted ferrule, said terminal block having an upper terminal seat disposed beneath the slot in said casing, a third terminal member intermediate the ends of said casing comprising a substantially annular band having 70 a flat terminal seat disposed within the casing beneath the slot therein, a fusible link secured removably to the terminal seats of said third terminal member and said terminal block, a heating element extended longitudinally 75 through said inner tube, end caps comprising line terminals removably screw threaded on said terminal ferrules and electrically connected with the ends of said heating element, an outer tubular casing closely surrounding 80 said inner tube and rotatable thereon arranged to provide a closure for the slot therein, said outer tube having a longitudinal slot therein through which said fusible element may be removed when the slot in said outer 85 casing has been rotated to register with the slot in said inner casing. 90
18. A thermal cut-out for the pilot circuit of an electrically operated switch having the combination of a tubular enclosing casing, 95 end caps removably located on the ends of the casing constituting line terminals of the cut-out, an intermediate terminal carried by the casing between said end caps, a fusible element electrically connecting said third 95 terminal and one of said end caps, and an outer tubular casing closely surrounding said inner tube between said third terminal and said end cap and freely rotatable thereon, said inner and outer tubular casings having 100 longitudinal slots therein through which said fusible element can be removed when said slots are in superimposed position. 105
19. A thermal cut-out including an inner tubular shell having a longitudinal slot therein, exteriorly screw threaded metal ferrules on the ends of said shell, one of said ferrules having a slot which is aligned with the slot in said shell, a terminal ring surrounding said shell intermediate its ends having a U- 110 shaped peripheral portion thereof extended into said shell through the slot therein and comprising a terminal engaging seat, a terminal block fixed in the slotted end of said tube having a terminal attaching seat disposed beneath the aligned slots in said tube and ferrule, a fusible element comprising a pair of links having one end thereof secured to the terminal seat of said third terminal member and contact block respectively and having their other and abutting ends releasably connected electrically by a fusible metal, terminal caps screw threaded to said ferrules, terminal caps screw threaded to said ferrules, one of which caps forms a closure for the slot in said slotted ferrule, an outer insulating 115 tube closely surrounding and rotatable on said inner tube between said third terminal member and said slotted ferrule having a longitudinal slot therein through which said fusible element is adapted to be removed 120 125 130

when both slots are aligned, and a heating element extended through said casing and connected electrically with said terminal caps.

20. A thermal cut-out including a tubular casing of insulating material having a longitudinal slot therein, terminal members comprising line terminals of the cut-out fixed to the ends of said casing a third terminal member carried by said casing intermediate the ends thereof having a U-shaped peripheral portion extended into said casing through the slot therein, said U-shaped portion providing a terminal seat, a fusible element having a portion thereof disposed in the longitudinal axis of said casing and having offset attaching portions which are detachably secured to the seat of said third terminal member and to a line terminal of the cut-out, a heating element extended through said casing and electrically connected with said end terminal members, said heating element arranged to lie closely adjacent the offset portion of said fusible element, and means providing a removable closure for the slot in said inner tubular casing.

21. A thermal cut-out including a tubular casing of insulating material having a longitudinal slot therein, terminal members comprising line terminals of the cut-out fixed to the ends of said casing, a third terminal member carried by said casing intermediate the ends thereof having a U-shaped peripheral portion extended into said casing through the slot therein, said U-shaped portion providing a terminal seat, a fusible element having a portion thereof disposed in the longitudinal axis of said casing and having offset attaching portions which are detachably secured to the seat of said third terminal member and to a line terminal of the cut-out, a heating element extended through said casing and electrically connected with said end terminal members, said heating element arranged to lie closely adjacent the offset portion of said fusible element, and means providing a removable closure for the slot in said inner tubular casing, said means including a concentric outer tubular casing rotatably received on said inner tube and having a longitudinal slot therein arranged to be moved into and out of covering relation with the slot in said inner tube by the rotation thereof.

22. A thermal cut-out of the cartridge type including the combination of an inner tubular insulating shell having a longitudinal slot therein, terminal ferrules surrounding and fixed to the ends of said shell, one of said ferrules having a slot therein coincident with the slot in the shell, a terminal block disposed beneath the slot in said ferrule having terminal attaching means disposed beneath said slot, an intermediate terminal member carried externally by said shell comprising a substantially annular member having a de-

pressed peripheral portion thereof extended through the slot in said shell and having terminal attaching means beneath the open slot therein, terminal caps removably screw threaded on said terminal ferrules, one of said caps constituting a closure for the slot in said slotted ferrule, terminal washers disposed within said terminal caps having passages therethrough, a heating element extended longitudinally through said shell having its terminals extended through said passages and reflexed along the outer faces of said terminal washers, and a fusible element located alongside and closely adjacent said heating element beneath the slot in said shell and having its terminals removably secured beneath the terminal attaching means of said third terminal member and said terminal block, whereby to permit removal of said fusible element through the slotted side wall of said shell.

23. A thermal cut-out of the cartridge type including the combination of an inner tubular insulating shell having a longitudinal slot therein, terminal ferrules surrounding and fixed to the ends of said shell, one of said ferrules having a slot therein coincident with the slot in the shell, a terminal block disposed beneath the slot in said ferrule having terminal attaching means disposed beneath said slot, an intermediate terminal member carried externally by said shell comprising a substantially annular member having exposed terminal attaching means beneath the open slot therein, terminal caps removably screw threaded on said terminal ferrules, one of said caps constituting a closure for the slot in said slotted ferrule, terminal washers disposed within said terminal caps having passages therethrough, a heating element extended longitudinally through said shell having its terminals extended through said passages and reflexed along the outer faces of said terminal washers, and a fusible element electrically connecting said third terminal and terminal block comprising a pair of links having horizontal attaching portions which are secured removably to said third terminal and terminal block respectively by the attaching means thereof, and having offset abutting heat-absorbing portions which are releasably connected electrically together by a fusible mass, one of said links having its attaching portion reflexed whereby to bias the offset portion thereof constantly into a position free from its abutting cooperating link.

24. A thermal cut-out including an insulating enclosing shell having a top opening at one end thereof, screw threaded terminal members carried by the ends thereof, one of said terminal members arranged to form a closure for said top opening, a heating element extended through said casing and connected electrically at its ends with said terminal members, an intermediate terminal mem-

ber having a top portion thereof extended downwardly within said insulating shell, a fusible link disposed within said shell alongside said heating element and electrically connected at one end with said intermediate terminal member, a terminal block fixed in said shell beneath said top opening and electrically connected with an end terminal thereof, and means accessible through said top opening for attaching the free end of said fusible element to said terminal block.

25. A thermal cut-out including a tubular insulating shell having a top opening at one end thereof, end terminal members screw threaded to said shell, one of said terminal members forming a closure for said top opening, an intermediate terminal member carried by said shell having a peripheral portion thereof extended downwardly within said shell to provide an externally exposed terminal seat, a terminal block having a terminal seat disposed within said shell beneath said top opening and electrically connected with an end terminal of said shell, a fusible link extended between the terminal seats of said 25 intermediate terminal member and said terminal block, terminal engaging means to secure said fusible link releasably in the aforesaid position, and a heating element disposed in said shell alongside said fusible link.

30 In testimony whereof, I have signed my name to this specification.
